DESIGN FOR A SHOE

Irving Grossman, New York, N. Y.

Application December 3, 1934, Serial No. 54,234

Term of patent 3½ years

To all whom it may concern:

Be it known that I, Irving Grossman, a citizen of the United States, residing in New York, in the county of New York and State of New York, have invented a new, original, and ornamental Design for a Shoe, of which the following is a specification, reference being had to the accompanying drawing, forming part thereof.

I claim:

The ornamental design for a shoe, as shown.

IRVING GROSSMAN.
